UNITED STATES PATENT OFFICE.

EUGENE T. KIEFFER, OF CHEYNEY, PENNSYLVANIA, ASSIGNOR TO VICTOR TALKING
MACHINE COMPANY, A CORPORATION OF NEW JERSEY.

DESIGN FOR A CABINET FOR SOUND PRODUCING AND REPRODUCING INSTRUMENTS.

Application filed October 12, 1927. Serial No. 23,729. Term of patent 14 years.

To all whom it may concern:

Be it known that I, EUGENE T. KIEFFER, a citizen of the United States of America, and a resident of Cheyney, Pennsylvania, have invented a new and original Design for Cabinets for Sound-Producing and Reproducing Instruments, of which the following is a specification, reference being had to the annexed drawing, forming a part thereof, and which

shows a perspective view of a cabinet embodying my new design.

I claim:

The ornamental design for a cabinet for sound-producing and reproducing instruments as shown.

In testimony whereof I have signed this specification.

EUGENE T. KIEFFER.
